UNITED STATES PATENT OFFICE.

GRAF GEORG VON ARCO AND AUGUST LEIB, OF BERLIN, AND AUGUST FREY, OF NON-NENDAMM, NEAR BERLIN, GERMANY, ASSIGNEES TO GESELLSCHAFT FÜR DRAHTLOSE TELEGRAPHIE, M. B. H., OF BERLIN, GERMANY.

RADIOTELEGRAPHY-STATION.

1,178,890.

Specification of Letters Patent. Patented Apr. 11, 1916.

Application filed November 1, 1911. Serial No. 658,063.

To all whom it may concern:

Be it known that we, GRAF GEORG VON ARCO and AUGUST LEIB, subjects of the German Emperor, and AUGUST FREY, a subject of the Austro-Hungarian Emperor, and residing, respectively, at Berlin and Nonnendamm, near Berlin, Germany, have invented certain new and useful Improvements in Radiotelegraphy- Stations, of 10 which the following is a specification.

This invention relates to radio-telegraphic and radio-telephonic stations.

In general, each radio-telegraphic and radio-telephonic station employs only one 15 antenna or aerial which is connected with the transmitting apparatus for transmitting and with the receiving apparatus for receiving. The change over from the transmitting into the receiving position, and reversely, 20 has until recently been brought about by special, manually-operated switches. Recently, it has been frequently desirable to be able to reverse in dependence on the key in such manner that when the key is depressed the apparatuses are connected for 25 transmitting whereas when the key is released they automatically return to the receiving position. Various means for this purpose have been known heretofore. The technical difficulties met with are principally that 30 the switching devices must synchronously follow the movements of the key, the difficulties being increased still more by the interruption of circuits, in part carrying high 35 tension currents. Consequently, in somewhat large stations there is a very great expenditure of energy in consequence of the large number of switches, and great wear and tear owing to the rapid opening and 40 closing of the same. In addition, having regard to the latter circumstance, the speed of telegraphing had to be reduced.

A primary object of this invention is to obviate these defects.

According to the invention the switching 45 device is provided with means such that when the key is released a change-over from the transmitting into the receiving position does not at once take place, while these 50 means exercise no influence or do not necessarily exercise any influence on the reverse movement from the receiving into the transmitting position. Therefore in this arrangement the apparatuses no longer re-

turn again into the receiving position whenever the key is released when the subsequent movement of the key takes place earlier than the change-over occurs. Such a switching arrangement which acts slowly one way may be employed for any desired modes 55 of connections of the stations; the receiving and transmitting apparatuses may be connected in series, in which event the receiver will be short-circuited when the transmitting apparatus is being used, or the 60 receiving and transmitting apparatuses may be alternately interpolated in the antenna. In these cases the operations to be brought about by a slow-acting relay are as follows: If, after finishing transmitting, receiving is to take place, firstly the primary heavy current must be interrupted, secondly the transmitting apparatuses must be disconnected from the antenna, and, thirdly, the receiving apparatuses must be connected 65 with the antenna. When it is required to change over from the receiving position to transmitting, firstly the receiving apparatuses must be disconnected from the antenna, secondly the transmitting apparatuses must be connected to the antenna, and, thirdly, the transmitting heavy current circuit must be closed. All these functions are 70 to be brought about by simply depressing and releasing the key.

With these objects in view, the invention consists in the parts, improvements and combinations more particularly described hereinafter and pointed out in the claims.

The invention is represented by way of 90 example in the accompanying drawings, wherein:

Figure 1 is a diagram showing the complete connection of a station in which the change-over members are coupled with a 95 braking member; Fig. 2 shows another form of the connection, in which, instead of the braking member, an elastic connection is connected between the telegraph key and a reversing switch, and Fig. 3 shows the contacts of the antenna change-over switch in 100 a position in which the antenna is connected with the transmitting circuit.

The general arrangement of the transmitting and receiving circuits and their connections with the antenna is in substance alike in both modifications shown in the Figs. 1 and 2.

Referring to Fig. 1, the antenna 1 is connected with a switch contact plate 21, and the transmitting circuit is connected by a conductor 51 to a like plate 21, both plates being mounted on porcelain insulators 50.

In the connection for receiving, the antenna 1 is connected by the knife switch 2 through its plate 21 with the receiving apparatus 3. If it is required to change to transmitting by depressing the key 4, a relay coil 5 is energized by the battery 6, and the core 7 of this coil is attracted. The bridge 8 of the relay is lifted from the lower contacts 38 and closes the upper contacts 9, and now current flows from the battery 6 over the contacts 9 to the coil 10, then over the contact spring 11 and the contact piece 12, which is rigidly connected with the rod 14, back to the battery. In the coil 10 is an iron core 13 which is connected with a second iron core 15 of a coil 16 by the rod 14 composed of non-magnetizable material. The coil 16 has a contact spring 17 similar to the spring 11. When the coil 10 is energized the iron core 13 is drawn to the right into it, the spring 11 no longer contacts with the contact piece 12 and the contact 17, 12 is closed. The movement of the cores 13, 15 is imparted to a rod 18 for actuating the knife switch 2 and the spring pressed contact brush 20, which bears against plates 21 when closed. To this end, the rod 18 is pivotally attached to the relatively short arm 36 of the knife switch 2 and is provided with a slot 18^a in which the relatively long arm 37, integral with a cam or eccentric 19 is guided. On this cam rests contact brush 20. Consequently, the same movement of the rod 18 imparts to the switch 2 a long stroke of small power and to the brush 20 a short stroke of great power. Accordingly, the change-over of the apparatus is brought about by a system comprising two coils each of which tends to draw into its middle portion an iron core. One of these coils switches the apparatus to transmitting and the other to receiving.

As soon as the rod 18 is moved to the right the switch 2 is opened, the contact brush 20 is powerfully pressed against the contact pieces 21 and the condenser circuit is connected to the antenna. This condenser circuit comprises the capacity 22, self-induction 23 and the spark-gap 24. The elements are shown in this position in Fig. 3.

When the key 4 is depressed a current simultaneously flows, however, through a relay coil 25 whereby its core 26 is lifted against the contacts 27. The current from the alternating current machine 28 is hereby conducted over transformer winding 30, the contacts 34, 35, (which are then closed by bridge 35^a, as will be explained hereinafter), contacts 27 and a choking coil 29; consequently a current is induced in the second-

ary winding 31 which feeds the condenser circuit. The relay 25, 26 accordingly operates synchronously with the movements of the key 4.

The relay 5, 7, on the contrary, should not move synchronously. When the key 4 is depressed the relay core 7 should be rapidly attracted, whereas when the key is released it should not at once close the contacts 38 again, because this would at once cause the arrangement to be returned to receiving. This is brought about by connecting the relay core 7 with a hydraulic or pneumatic brake which may have the form of a dash pot. This dash pot comprises a cylinder 39 in which moves the piston 40 coupled with the relay core 7. The cylinder is provided with a check valve 41 which allows the contents of the cylinder to free issue therefrom when the piston rises, but not to reenter same. A small lateral opening whose size can be adjusted as desired by a regulating screw 42, serves for the gradual admission of the fluid, in this case air. In this manner we attain that the bridge 8 contacts with the lower contact piece 38 only several seconds after the key 4 has been released.

Now it must be arranged that the heavy current circuit can be closed by the key relay 25, 26 only after the change-over of the antenna from the receiving into the transmitting position is terminated. Otherwise, in the case of deficient attention, the heavy transmitting currents would be able to pass through the receiving apparatus and destroy the same. For preventing this possibility the following arrangement is made: The knife switch 2 has connected with it an additional contact arm 43 which closes the contacts 32 only after the knife switch has been opened. These contacts are connected over the battery 6 with the relay coil 33. When the contacts 32 are closed the coil 33 receives current from the battery 6, attracts its armature 34 and closes the alternating current contacts 35 by means of bridge 35^a. Accordingly, the alternating current can only now flow through the transformer 30, 31 and the transmitter can only now be thereby energized.

If, on the other hand, the operator's key is released, a longer period than the dash pot permits its piston to descend, bar 8 again has arrived at its low position, wherein it closes contacts 38 so that thereby a circuit is closed from battery 6 over contacts 38, solenoid 16, contact spring 17, plate 12 (which latter is then in contact with 17) back to the battery. Core 15 is drawn in thereupon and rod 14 shifted to the left into the position shown in Fig. 1. This likewise shifts rod 18 to the left and thereby opens first contacts 32 and thus opens the generator circuit at 35, and thereupon knife switch 2 is closed, which again

connects the antenna 1 to the receiver circuit. Simultaneously plate 12 slides off contact 17 and onto 11 and thereby sets the circuit for energizing solenoid 10. However, 5 the movement of cam 19, which operates transmitter switch 20, 21, is arranged so that this switch is only open after knife switch 2 is closed. In this manner we secure the result that the antenna is always connected 10 with the ground and cannot electrically freely oscillate for a certain time. When the atmosphere is highly charged electrically a short moment of free electric oscillation would suffice for charging the antenna 15 and for discharging it with great force at the receiver ground. This discharge would then take place over the detector and destroy the same.

In the illustrative embodiment according 20 to Fig. 2 the contacts are directly controlled by the telegraph key 4, which is pivoted at 4^a by means of an insulated portion so that no electrical connection exists between battery 6 and key 4.

25 When transmitting is to take place the key 4 is moved out of the position shown in dotted lines into the transmitting position shown in full lines. The rear end of the key is connected with a switch 44 which 30 alternately connects the negative pole to battery 6 in circuit with one of the two contacts 45, 46. Fig. 2 shows the device in the condition in which switch 44 has just been closed, so that the direct current consequently flows from the negative pole over switch 44, contact 45, coil 10 and contacts 11, 12, to the positive pole of battery 6. As 35 mentioned with reference to Fig. 6, the core 13 is thereby attracted, the receiving contact 2 opened and the transmitting contact 20, 21 closed. After these latter contacts are 40 closed and antenna 1 is connected in to the secondary oscillation circuit of the transmitting system, lower switch 43, 32 is closed which similarly to the manner described and 45 shown in Fig. 1, closes a circuit over battery 6 which energizes relay coil 33, which by attracting its core 34 closes contact points 35 through bar 35^a so that the circuit from 50 generator 28 over inductance 29, key 4, contacts 35, primary coil 30 is set thereby, ready to be closed by key 4 at its contacts 47, 47^a when signals are to be transmitted.

The switch 44 which is insulated from the 55 key 4 has lost motion connection therewith in such manner that the key can perform the small rocking motions necessary in transmitting signals without operating switch 44 thereby. Accordingly, when 60 transmitting, the contact 44, 45 remains closed and the contact 4, 47 for the transmitter relay is closed only alternately. When receiving is to take place again, the key is lifted into the position shown in 65 dotted lines and then drives the switch 44

into its position likewise shown in dotted lines. This breaks the circuit through relay 10 and closes the circuit through relay 16 with the same effect as described before with reference to Fig. 1, so that thereby the 70 generator circuit is first interrupted at 35, 35, then the antenna connected by switch 2 to the receiver circuit and then disconnected from the transmitter circuit.

We claim:

1. In a radio-telegraphic station, the combination of an antenna, means comprising a transmitter feeding circuit for generating electric oscillations, having a key, means for transmitting and means for receiving oscillations, switching devices for operatively connecting said transmitting and receiving means alternately to and disconnecting the same from the said antenna, said key being adapted to cause the movement of said 80 switching devices into transmitting position when it is closed, and into receiving position when it is open, and means for preventing the switching devices from moving into their receiving position when the key moves 85 from its transmitting position during the normal succession of the elements of the signaling code.

2. In a radio-telegraphic station, the combination of an antenna, means comprising a transmitter feeding circuit for generating electric oscillations, having a key, means for transmitting and means for receiving oscillations, a switching device comprising a pair of receiving contacts for connecting the receiving means to and disconnecting the same from the antenna, a second switching device comprising a pair of transmitting contacts for connecting the transmitting means to and disconnecting the same from the antenna, a common actuating device for both of said switching devices for alternately opening and closing said devices, said key being adapted to cause the movement of the 95 said actuating device when the key moves into or out of transmitting position, and means for preventing the switching devices from moving into their receiving position when the key moves from its transmitting 100 position during the normal succession of the elements of the signaling code.

3. In a radio-telegraphic station, the combination of an antenna, means comprising a transmitter feeding circuit for generating electric oscillations, having a key, means for transmitting and means for receiving oscillations, a switching device comprising a pair of receiving contacts for connecting the receiving means to and disconnecting the same from the antenna, a second switching device comprising a pair of transmitting contacts for connecting the transmitting means to and disconnecting the same from the antenna, a common driving device for said 110 switching devices, said key being adapted to 115

- cause the movement of the said driving device when the key moves into and out of transmitting position, said driving device having suitable lever connection to operate 5 said transmitting contacts a short distance at great pressure and the receiving contacts a large distance at small pressure when the key moves into and out of transmitting position, and means controlled by said key for 10 preventing the switching devices from moving into their receiving position when the key moves from its transmitting position during the normal succession of the elements of the signaling code.
- 15 4. In a radio-telegraphic station, the combination of an antenna, means comprising a transmitter feeding circuit for generating electric oscillations, having a key, means for transmitting and means for receiving electric oscillations, a switch comprising a lever having one long and one short arm for connecting the receiving means to and disconnecting the same from the antenna, a contact brush having a large contact face for connecting the transmitting means to and disconnecting the same from the antenna, a lever having unequal arms for moving said brush, a common driving device attached to the short arm of the former lever, and the 20 long arm of the latter lever, two relay cores, a rod of non-magnetizable material connected with said cores and said driving device, two relay coils surrounding said relay cores, a key for closing and opening the transmitter feeding circuit and for energizing said relay coils, and means for preventing the said levers from being actuated when the key is opened during the normal succession of the elements of the signaling code.
- 25 5. In a radio-telegraphic station, the combination of an antenna, means comprising a transmitter feeding circuit for generating electric oscillations, having a key, means for transmitting and means for receiving oscillations, switching devices and electro-magnetic operating means therefor for alternately connecting said transmitting and receiving means into and disconnecting the same from the said antenna, comprising a 30 change-over switch operatively connected with said electro-magnetic means, for causing in one of its positions the connection of the receiving means and in the other position of the transmitting means to said antenna. 35 said key having lost motion connection with the said change-over switch to permit freedom of key movement at a small throw for transmitting telegraphic signals without operating the switch, but to cause operation of 40 said switch at a large throw of said key.
- 45 6. In a radio-telegraphic station, the combination of an antenna for generating electric oscillations, having a key, means for transmitting and means for receiving oscillations, switching devices for alternately

connecting said transmitting and receiving means and disconnecting the same from the said antenna, said key being adapted to cause the movement of said switching devices, and means for retarding the disconnection of the transmitting means and the connection of said receiving means by said switching devices, said retarding means adapted to permit an unretarded disconnection of said receiving means and connection of said transmitting means by said switching devices.

7. In a radio-telegraphic station, the combination of an antenna, means comprising a transmitter feeding circuit for generating electric oscillations, having a key, means for transmitting and means for receiving oscillations, switching devices for alternately connecting said transmitting and receiving means to and disconnecting the same from the said antenna, said key being adapted to cause the movement of said switching devices, and regulatable means for retarding the disconnection of the transmitting means and the connection of said receiving means by said switching devices, said retarding means adapted to permit an unretarded disconnection of said receiving means and connection of said transmitting means by said switching devices.

8. In a radio-telegraphic station, the combination of an antenna, means comprising a transmitter feeding circuit for generating electric oscillations, having a key, means for transmitting and means for receiving oscillations, switching devices for connecting said transmitting and receiving means to and disconnecting the same from the said antenna, relays controlled by said key for actuating said switching devices, and means controlled by said key for preventing the switching devices from moving into their receiving position when the key moves from its transmitting position during the normal succession of the elements of the signaling code.

9. In a radio-telegraphic station, the combination of an antenna, means comprising a transmitter feeding circuit for generating electric oscillations, having a key, means for transmitting and means for receiving oscillations, switching devices for alternately connecting said transmitting and receiving means into and disconnecting the same from the said antenna, a relay controlled by said key for closing and opening the transmitter feeding circuit, a second relay directly controlled by said key for controlling the operation of said switching devices, and means connected with the latter relay for retarding the change-over of the switching devices from the transmitting into the receiving position, said means permitting unobstructed movement of said devices from the receiving into the transmitting position.

10. In a radio - telegraphic station, the combination of an antenna, means comprising a transmitter feeding circuit, for generating electric oscillations, having a key, 5 means for transmitting and means for receiving oscillations, switching devices for alternately connecting said transmitting and receiving means to and disconnecting the same from the said antenna, said key 10 being adapted to cause the movement of said switching devices, means for closing said feeding circuits, means connected with the switching devices for causing said closing means to operate only after the receiving 15 means are disconnected from the antenna, and means for preventing the switching devices from immediately moving into their receiving position when the key moves from its transmitting position.
20. 11. In a radio - telegraphic station, the combination of an antenna, means comprising a transmitter feeding circuit for generating electric oscillations, having a key,
- means for transmitting and means for receiving oscillations, switching devices for connecting said transmitting and receiving means to and disconnecting the same from the said antenna, said key being adapted to cause the movement of said switching devices, means for closing said feeding circuit, means connected with the switching devices for causing said closing means to operate only after the receiving means are disconnected from the antenna, and means for preventing the switching devices from immediately moving into their receiving position when the key moves from its transmitting position.

In testimony whereof we affix our signatures in the presence of two witnesses. 40
